UNITED STATES PATENT OFFICE.

JOSIAH T. MANGHAM, OF RAINEY'S CREEK, TEXAS.

IMPROVEMENT IN PULVERIZING SUBSOIL-PLOWS.

Specification forming part of Letters Patent No. **155,249**, dated September 22, 1874; application filed June 20, 1874.

To all whom it may concern:

Be it known that I, JOSIAH T. MANGHAM, of Rainey's Creek, in the county of Coryell and State of Texas, have invented a new and valuable Improvement in Pulverizing Subsoil-Plow; and I do hereby declare that the following is a full, clear, and exact description of the construction and operation of the same, reference being had to the annexed drawing making a part of this specification, and to the letters and figures of reference marked thereon.

Figure 1 of the drawing is a representation of side view of my plow. Fig. 2 is a plan view of the same. Fig. 3 is a detail view of the same.

This invention has relation to subsoil-plows, which are also designed for pulverizing the soil; and it consists in a novel manner of applying the upper end of the plow-standard to the beam, whereby the standard can be adjusted both laterally and vertically in the arc of a circle, and any desired degree of inclination given to it, as will be hereinafter explained.

In the annexed drawings, A designates the beam of the plow, and B B the handles thereof. C designates a metal standard, which has secured to it the mold-board D and landside bar b. The front edge of the standard C and the front surface of the mold-board present a gradual curve from the plow-point to the plow-beam. The upper end of the standard has constructed on it a broad head, C', the rear end of which has a curved slot, h, through it, for receiving a bolt, F, which passes up through a slot, g, in the beam A,

and receives on its upper end a washer, f, and a nut, f'. The front end of the head is constructed with a notch, i, which receives a loop, E, that embraces the beam A, and is confined in place by means of a tie-plate, e, and nuts e'. The standard is by these means rigidly secured to the beam A, and by loosening the nut f' the point of the mold-board can be adjusted laterally for taking more or less land.

By reference to Fig. 1 it will be seen that the upper end of the head C' is convex—that is to say, it presents a segment of a circle; also, that the surface of the beam A, against which the head C' is confined, is concave, the arc being much longer than that of the head C'. The object of this construction is to allow the plow-point to be inclined more or less according to the depth it is desired to run in the ground. This adjustment is effected by loosening the nuts f' e' and moving the head C' forward or backward.

What I claim as new, and desire to secure by Letters Patent, is—

The curved head C' of the plow-standard C, having at its rear end a curved slot, h, in combination with beam A, having slot g, the bolt F, and nuts, substantially as and for the purpose set forth.

In testimony that I claim the above I have hereunto subscribed my name in the presence of two witnesses.

JOSIAH T. MANGHAM.
